UNITED STATES PATENT OFFICE.

DAVID LEMIEUX, OF LEWISTON, MAINE.

CUTTING MECHANISM FOR AUTOMATIC LOOMS.

Application filed January 25, 1927. Serial No. 163,456.

This invention is a shear device to be attached to an automatic loom preferably of the Stafford or Crompton-Knowles pattern as well as the so-called Draper loom on which are manufactured cotton goods, sheeting, table linen, etc. and it is an object of the invention to provide for the attachment of the device to the loom in such a manner that it will operate to simultaneously pull or hold the filling and cut the same close to the selvage each time the loom doffs. As understood in the art, the "doffing" process takes place automatically when the loom changes shuttle.

As is well understood in the art, in the ordinary operation of a cotton goods manufacturing plant, it is necessary to employ at least one operative to each loom to go over all of the cloth, inspecting same and picking out knots, burrs, loose threads, etc., every foot or so in the material. This operation is known as "burling," and is performed by the cloth room help. By reason of this invention, however, the necessity for "burling" is reduced to a minimum, if not indeed entirely eliminated by reason of the fact that the filling or thread being cut close to the selvage is not pulled back into the filling to make a homely and irregular thread in the cloth.

A further object of the invention is to provide an attachment of the character described which embodies substantially few working parts of simple and practical construction and which can be readily adjusted to fit the loom with little or no alteration of the latter.

Additional objects will be apparent from the following description of the device and from the accompanying drawings, wherein:

Figure 1 is an elevational view of the attachment as seen from one side thereof.

Figure 2 is a similar view as seen from the opposite side.

Figure 3 is a cross section view on line 3-3 of Figure 2.

Figure 4 is a fragmentary plan view of the attachment illustrating the jaw-face construction.

Figure 5 is an elevational view illustrating the attachment in play on a loom.

Figure 6 is a diagrammatic view of the parts shown in Figure 5.

Figure 7 is a detail view of one of the jaw members of the attachment.

This knife or shear is composed of the

pivoted members 1 and 2, which are so formed as to provide relatively upper and lower thread gripping jaws 3 and 4. The gripping of the thread is aided by the attachment of a small piece of felt 5 to the jaw face of the lower jaw 1 and by providing the upper jaw 2 with grooves 6, as shown. The upper jaw 2 has a cutting or shearing edge 7 adapted to cooperate with a similar edge 8 on the blade 9 carried by the lower jaw 1. Blade 9 extends just far enough above the gripping face of the lower jaw to enable the knife or shear to cut the thread and grip the loose end almost simultaneously. To allow for the convenient attachment thereto of the blade 9, the lower jaw may be provided, on its bottom side and co-extensive with one edge thereof, with a depending shoulder or extension 10 against the face of which the blade is held by the attaching screws 11 engaging the threaded openings 12 in the shoulder. The openings in the blade through which the attaching screws extend are not threaded and, hence, the blade is free to slide on the screws under certain conditions, as when the screws are loosened. As will be seen in Figure 4, the confronting faces of the blade 9 and the jaw shoulder 10 have relatively aligned recesses co-acting to provide spring pockets 13 in each of which is a small helical spring 14. These springs, being normally compressed, exact a continuous outward thrust against the blade and serve to keep the same tight against the heads of the attaching screws. Follower screws 15 are also threadedly engaged in the jaw shoulder 10 and have their ends receivable in suitable cavities or seats 16 formed in the blade 9, as illustrated.

The jaws are normally retained in closed position by means of a tensioning device which may consist of a helical spring 17 having one end attached to the upper jaw member at 18 and having the other end attached to a part 19 mounted on the extension 20 of the lower jaw member which extension serves as a handle for attaching the device to the loom. The member is attached to the loom in such manner that the blade 9 runs along the selvage of the cloth being manufactured and for this purpose the end of the handle 20 is secured by the fasteners 21 to the breast beam 22 of the loom with the knife disposed rearwardly thereof and at right angles to the lay 23 of the loom, the arrangement being

such that the jaws will not be higher than the upper surface 24 of the lay. Since the knife or shear travels over the lay, the latter is altered for the purpose of the invention by cutting off a small section, as at 25, in order to pass the knife. The dotted line in Figure 5 indicates where the knife travels over the lay through space in reed 26.

In the operation of the device, the jaws are automatically opened by the operating means hereinafter described and which includes as one of its elements the vertically reciprocating transfer arm 27 of the loom. Connected to this arm, as at 28, is a laterally extending rod 29 of irregular shape to fit the loom and provided at its outer extremity with a horizontally disposed pivotally mounted finger 30 adapted to strike against a pin 31 on the upper jaw member. The striker finger 30 is normally maintained in substantially horizontal position by a helical spring 32 and is limited in its upward movement by the shoulder 33.

In the operation of the loom, when the transfer arm moves downwardly for the purpose of changing the bobbin in the shuttle, the rod 29 moves down also and causes the finger 30 to strike and press down on the pin 31 which opens the jaws of the knife or shear. The finger 30 is so bevelled on the edge that it allows the pin to slip past after the jaws have been sufficiently opened or separated and the tensioning spring 17 is then free to act for closing the jaws again.

By this arrangement the knife is able to catch the staple thread and to cut the same near the cotton, the felt and the grooves of the jaws aiding them in gripping and holding the loose end of the filling. There will, therefore, be no staple thread from the bobbin which may be woven into the filler and cause an irregularity.

From the foregoing description, the advantages of construction and the method of operation will be readily apparent to those skilled in the art to which the invention relates, and it is to be understood that the device shown is merely illustrative and that such changes may be made, when desired, as are within the scope of the appended claims.

Having thus described the invention, what is claimed is:

1. A cutter attachment for a loom comprising a pair of relatively pivoted members having coacting jaws and cutters, one of said members having an extension serving as a handle for attaching the device to the loom, jaw tensioning means normally holding the jaws and cutter in closed position, a projecting pin on one of said jaws, an operating rod, a pivoted finger carried by the rod and projecting over the said pin to press down on the latter for opening the jaws and cutters when the said rod is moved downwardly, said finger being free to swing

downwardly from the horizontal but restricted from any upward movement above the horizontal, said finger being beveled to allow the pin to slip past after the jaws and cutters have been opened, and a spring for normally retaining the finger in horizontal position.

2. A cutting mechanism for automatic looms comprising a stationary knife having one end fixed to the breast beam of the loom and its other end disposed towards the lay of the loom and formed to present a flat clamping jaw having a cutting edge, a movable knife pivoted to the stationary knife and also formed to present a flat clamping jaw having a cutting edge, said pivoted cutter having an abutment thereon, tensioning means normally holding the jaws closed, transfer mechanism, and an operating member depending from the reciprocating arm of the transfer mechanism and adapted to strike the abutment of the said pivoted knife to move the latter into open position, said abutment and said operating member having co-acting abutting faces permitting them to slide past each other when the said knives are open a predetermined extent.

3. A cutting mechanism for automatic looms comprising a pair of pivoted cutters presenting relatively upper and lower clamping surfaces, one of said cutters having a cutting edge and the other cutter having a depending shoulder, a knife secured to said shoulder, and thrust means between the said knife and the said shoulder.

4. A cutting mechanism for automatic looms comprising a pair of relatively pivoted cutters presenting relatively upper and lower clamping surfaces, one of said cutters having a cutting edge and the other cutter having a depending shoulder, a knife adjustably secured to said shoulder, and tensioning means between the said knife and the shoulder for exerting outward thrust against the said knife.

5. A cutting mechanism for automatic looms comprising a cutter fixed to a stationary part of the loom and presenting a flat clamping jaw having a cutting edge, a cutter pivoted to the fixed cutter and having a clamping jaw adapted to co-act with the clamping jaw of the fixed cutter to clamp the filling thread therebetween a transfer mechanism, an operating rod carried by the reciprocating arm of the transfer mechanism for movement laterally of the said pivoted cutter, said pivoted cutter having an abutment thereon, and a lateral projection on said rod adapted to strike and press down on the abutment when the rod descends for opening the cutter, said projection being pivotally mounted to move freely out of the path of the abutment when the said rod ascends.

6. A cutting mechanism for automatic

looms comprising a pair of relatively pivoted cutters presenting flat contacting clamping jaws, one of said cutters being provided along one edge of the jaw with a cutting edge, the 5 other cutter having a depending shoulder, supporting screws threadedly engaged in said shoulder, a cutting blade supported on said screws, said blade and said shoulder having relatively aligned recesses co-acting to provide spring pockets, and springs with-¹⁰ in said pockets exerting continuous outward thrust on said blade.

In testimony whereof I hereunto affix my signature.

DAVID LEMIEUX.
